(57) **CLAIM**

The ornamental design for a package for liquids, as shown and described.

DESCRIPTION

FIG. 1 is a front, side perspective view of a first embodiment showing our new design, the undisclosed rear is not part of the claimed design;

FIG. 2 is a front, side perspective view thereof in a further orientation.

FIG. 3 is a front, side perspective view of a second embodiment showing our new design, the undisclosed rear is not part of the claimed design; and,

FIG. 4 is a front, side perspective view thereof in a further orientation.

The rear of the package for liquids not shown in the drawings or described in the specification forms no part of the claimed design. The left side of the package for liquids is a mirror image of the right side.
